UNITED STATES PATENT OFFICE.

PETER E. GUERIN, OF NEW YORK, N. Y.

DESIGN FOR DRAWER-PULLS.

Specification forming part of Design No. 7,708, dated August 18, 1874; application filed June 6, 1874.
[Term of Patent 3½ years.]

To all whom it may concern:

Be it known that I, PETER E. GUERIN, of the city, county, and State of New York, have invented a new and original Design for Drawer-Pull, of which the following is a specification:

The nature of my design for a drawer-pull is fully represented in the accompanying drawing, in which—

Figure 1 is a front elevation, and Fig. 2 is a side elevation.

The design consists of the plain border *a*, diagonal ribs *b*, curved ribs *c*, *d*, and *e*, and the chased or "matted" surface *f* on the head *A* of the screw; also, the plain border *g*, scroll *h*, and chased or matted surfaces *i* on the attaching-plate, *B*; also, the plain bands *l*, figured bands *m*, and chased or matted surface *n* of the handle *F*.

band *m*, and chased or matted surface *n* of the handle *F*.

I claim as my invention—

1. The plain border *a*, diagonal ribs *b*, curved ribs *c*, *d*, and *e*, and the chased or matted surface *f* on the head *A* of the screw, as set forth.

2. The plain border *g*, scroll *h*, and chased or matted surfaces *i* on the attaching-plate, as set forth.

3. The plain bands *l*, figured bands *m*, and chased or matted surface *n* of the handle *F*, as set forth.

PETER E. GUERIN.
